US00D923001S

(12) **United States Design Patent** (10) **Patent No.:** **US D923,001 S**
(45) **Date of Patent:** **** Jun. 22, 2021**

(54) **DISPLAY DEVICE**

(71) Applicants: **Samsung Display Co., Ltd.**, Yongin-si (KR); **UNIST (ULSAN NATIONAL INSTITUTE OF SCIENCE AND TECHNOLOGY)**, Ulsan (KR)

(72) Inventors: **Ja Eun Lee**, Suwon-si (KR); **Gyouhyung Kyung**, Ulsan (KR); **Ji Hyeon Yang**, Ulsan (KR); **Seungbae Lee**, Seoul (KR); **Byeonghwa Choi**, Seoul (KR); **Soo Yeon Seo**, Ulsan (KR); **Minjoong Kim**, Seoul (KR); **Sungryul Park**, Ulsan (KR); **Songil Lee**, Ulsan (KR); **Jihhyeon Yi**, Ulsan (KR); **Donghee Choi**, Ulsan (KR)

(73) Assignees: **Samsung Display Co., Ltd.**, Yongin-si (KR); **UNIST (Ulsan National Institute of Science and Technology)**, Ulsan (KR)

(**) Term: **15 Years**

(21) Appl. No.: **29/649,845**

(22) Filed: **Jun. 1, 2018**

(30) **Foreign Application Priority Data**

Dec. 5, 2017 (KR) 30-2017-0057322

(51) **LOC (13) Cl.** **14-02**

(52) **U.S. Cl.**

USPC **D14/344**

(57) **CLAIM**

The ornamental design for display device, as shown and described.

DESCRIPTION

FIG. 1 is a perspective view of the display device according to the present design;

FIG. 2 is a front view thereof;

FIG. 3 is a rear view thereof;

FIG. 4 is a left side view thereof;

FIG. 5 is a right side view thereof;

FIG. 6 is a top view thereof, with the bottom view being a mirror image thereof;

FIG. 7 is a perspective view of the display device in a bent state;

FIG. 8 is another perspective view of the display device in a bent configuration; and,

FIG. 9 is another perspective of the display device shown in FIG. 1 in an environment of use.

The broken lines showing a portion of a wristwatch and a hand in FIG. 8 and a smartphone in FIG. 9 depicts environmental subject matter and form no part of the claimed design.

1 Claim, 9 Drawing Sheets
